(57) **CLAIM**

The ornamental design for a suspension control arm for a motor coach, substantially as shown and described.

DESCRIPTION

FIG. 1 is a front, left side isometric view of a suspension control arm for a motor coach showing our new design.

FIG. 2 is a front view thereof.

FIG. 3 is back view thereof.

FIG. 4 is a left side view thereof.

FIG. 5 is a right side view thereof.

FIG. 6 is a bottom view thereof; and,

FIG. 7 is a top view thereof.

The broken lines in the figures depict portions of the suspension control arm that form no part of the claimed design.
